UNITED STATES PATENT OFFICE.

ALEXANDRA RICHTER, OF LEIPZIG, GERMANY.

STERILIZING APPARATUS.

949,661.

Specification of Letters Patent. Patented Feb. 15, 1910.

Application filed August 29, 1908. Serial No. 450,688.

To all whom it may concern:

Be it known that I, ALEXANDRA RICHTER, a subject of the German Emperor, and resident of Leipzig, Germany, have invented 5 an Improved Sterilizing Apparatus, of which the following is a specification.

The object of the present invention is a sterilizing apparatus in which the whole interior space can be utilized and in addition to this, receptacles of different sizes 10 may be put in said apparatus. This is attained by arranging the intermediate bottoms adjustably in their vertical direction.

In order that the invention may be more 15 clearly understood, reference is made to the annexed drawing, in which:—

Figure 1 shows a vertical section of the apparatus. Fig. 2 shows a plan, and Fig. 3 shows details.

20 In a kettle or pot *a* provided with a lid *b*, for the purpose of setting up the glasses, cans or the like, a body is inserted which corresponds to the size of the pot and whose three supporting pillars *c* are rigidly connected with the lower plate *d*. In accordance with the height of the cans which are 25 to be put inside, the intermediate plates *e* are inserted and adjustably fastened by means of the bolts *m* to the pillars *c* which 30 have holes therein adapted to receive the said bolts. The intermediate plates *e* are formed with central openings *d²*; the edges around said openings are bent to form seats for the plates *d¹*. By removing said plates 35 *d¹* a taller glass may be placed in the center of the device. By means of the handle *h*, which is removably secured to the ends of pillars *c*, the inserted body may be removed. The plates *d*, *e* and the plates *d¹* are 40 provided with a number of apertures *l* for the better circulation of the water or steam. Said plates also have a number of small apertures *g¹* into which lock the pins *g* of the saucers *f* which are adapted to receive 45 the cans so as to prevent the cans from being displaced or from sliding off. The bow *h¹* for closing the cans or glasses *w* is similar to those which are in use, only rounded in a considerably flatter fashion. Said bow is 50 provided at the top with a small socket-piece *r* into which the pin *g* of the saucer enters, and prevents tipping of the glasses.

The bottom *h* of the saucer *f* has a rectangular depression on its upper surface and 55 a slot *h^x* is formed in said bottom into which

is guided the pin *g* which is provided with a rectangular plate *g¹* which slides in said depression. Thus the parts may be adjusted to overcome small differences in the arrangement of the holes. Plate *g¹* and pin *g* are held in position by the inserted loose plate *i* and by the pressure of the glass set upon it.

I claim—

1. A sterilizing apparatus comprising a 65 kettle, a cover therefor, and a supporting body adapted to be placed in said vessel, said body comprising a lower perforated plate, upright pillars supported by said plate, perforated plates removably carried 70 by said pillars above the bottom plate, and a removable handle on the upper end of the pillars.

2. A sterilizing apparatus comprising a 75 vessel, perforated plates removably and adjustably supported therein, and saucers removably carried by said plates.

3. A sterilizing apparatus comprising a 80 kettle, plates removably and adjustably supported therein, said plates having a central opening with a supporting flange around the opening, and central removable plates covering said opening.

4. A sterilizing apparatus comprising a 85 kettle, a frame therein, plates adjustably carried by said frame one above the other, and adapted to receive the articles to be sterilized, saucers, a pin secured to the bottom of the saucer, each of said plates having perforations therein through which the 90 pins are adapted to pass, a cover for the article to be sterilized having a central depression into which the pin of the saucer immediately above the article to be sterilized extends. 95

5. A sterilizing apparatus comprising a 100 kettle, perforated plates supported therein, and saucers supported by said plates, each of said saucers having a depending pin slidably arranged on the bottom of the saucer and adapted to engage with one of the perforations in the plate.

In testimony whereof I have hereunto set my hand in the presence of two subscribing witnesses.

ALEXANDRA RICHTER.
